UNITED STATES PATENT OFFICE.

LYLE K. SNELL AND CHESTER F. JOHNSON, OF DETROIT, MICHIGAN, ASSIGNEES TO CADILLAC MOTOR CAR COMPANY, OF DETROIT, MICHIGAN, A CORPORATION OF MICHIGAN.

HYDROCARBON-MOTOR.

1,244,651.

Specification of Letters Patent. Patented Oct. 30, 1917.

Application filed February 2, 1916. Serial No. 75,634.

To all whom it may concern:

Be it known that we, LYLE K. SNELL and CHESTER F. JOHNSON, citizens of the United States, both residents of Detroit, Wayne 5 county, State of Michigan, have invented certain new and useful Improvements in Hydrocarbon-Motors, of which the following is a specification.

This invention relates to hydrocarbon 10 motors, and particularly to an improved means for feeding fuel to the carbureter or fuel mixing devices therefor.

In motor cars which have their fuel tanks arranged at a level which is normally 15 below that of the carbureter, it is customary to provide a vacuum, or pressure means for lifting the fuel from the tank to the carbureter, and in order to attain the most desirable operating conditions, it has been 20 found that only sufficient pressure or vacuum shall be supplied to the tank to lift the fuel to a certain height in the carbureter under normal conditions; that is, the level of the fuel in the carbureter shall not vary 25 above or below a certain height under any and all conditions.

However, it has also been discovered that when the vehicle is on an incline, so that the fuel tank is placed either above or below 30 its former level, relative to the carbureter, the pressure of the liquid feeding to the carbureter, is either increased or decreased. It will also be understood that for a given 35 pressure on the liquid in the tank there will be a variation in the pressure of the liquid adjacent the carbureter with every variation of the level of the liquid in the tank, even though the tank is maintained at an unchanged level, and the tendency will be to 40 vary the level of the fuel in the carbureter.

To obviate these, and other difficulties, we have provided means for maintaining a substantially uniform pressure of the fuel in the fuel feeding line at a point adjacent 45 the carbureter, regardless of the changes of position of the fuel tank, or changes of the level of the fuel in the tank.

Another object of this invention is to provide an automatic means for varying the 50 pressure in the gasoline tank, thus compensating for the changes of the level of the tank and thereby maintaining a substantially uniform pressure in the fuel feeding lines adjacent the carbureter.

55 Other objects will appear from the fol-

lowing description, taken in connection with the accompanying drawings, which form a part of this specification, and in which:

Figure 1 illustrates a fragmentary side elevation, with portions broken away, of a 60 power plant and power feeding system therefor, illustrated in diagrammatic form; and

Fig. 2 is an enlarged vertical sectional view of a preferred form of regulating device, embodied in my invention.

Referring to the drawings, 10 represents a motor base or crank case, on which a plurality of cylinder blocks may be arranged in V relation, and one of which is illustrated 70 at 11, as secured in position by bolts 12. A gas intake is shown at 13, to which a carbureter 14 may be secured, as by bolts 15. A source of fuel supply for the carbureter 75 may be kept in the usual tank 15', which may be swung from the rear end of the vehicle side members 16.

The motor crank shaft 17 has a gear 18, arranged on the front end thereof, and secured in position by means of a bolt 19. The 80 gear 18 is adapted to be suitably connected, as by a chain 20, to drive a gear 21, which is arranged on the front end of the usual valve cam shaft 22, and is secured in position thereon, as by the bolt 23. This gearing is adapted to be inclosed by a cover 24, arranged at the front end of the motor and on which a pump 25 may be mounted. This pump is of the well known reciprocating type, comprising a piston 26 and pitman 27, which is adapted to be driven by an eccentric 28, formed integral with the bolt 23 on the cam shaft 22. The pump 25 is adapted to supply air pressure for the tank 15' and is connected thereto by means 90 of the conduits 29 and 30, which are connected together by the valve casing 31. The construction is such that the fuel is adapted to be fed from the tank 15' to a settling chamber 32, by means of a pipe connection 95 33. The settling chamber is provided with a threaded nipple, 33', which is adapted to be secured to the carbureter 14. It will also be noted that the settling chamber is also provided with an intake port 35, which is adapted to be connected with the conduit 33, and a discharge port 36 is led into the interior of the float chamber 34, and its communication therewith may be controlled by the usual float 37 and its valve mecha-

nism 38. A fine mesh screen 39 may be arranged in the settling chamber between the intake port 35 and discharge port 36. The drain port 40, which is provided in the bottom of the settling chamber, may be closed by the plug 41.

A flexible diaphragm 42, of any suitable material, may be arranged over the opening 43, formed in the top of the chamber 32, and held in position by means of a ring, or cage member 44, which is held in position by means of the bolts 45'. It will be noted that the valve casing 31, hereinabove referred to, may be formed as an integral part of the cage 44, and may have arranged therein a valve mechanism, comprising a valve stem 45, having a conical portion 46, adapted to seat over a port 47, which leads to the atmosphere. This valve is adjustably maintained in position at its upper portion by means of an adjusting bolt 50, which may be threaded in a cap piece 51 arranged in the valve casing 31. It will be noted that the valve stem 45 has a lower extension 52 formed integral therewith, which is adapted to abut against the top of the diaphragm 42 and to be actuated thereby.

Having thus described the general construction and arrangement of the parts, it will be understood that the pump 25, which is provided, is adequate for maintaining the maximum pressure required in the fuel feeding system under extreme conditions, and the tension on the spring 48 in the valve mechanism is adjusted to maintain sufficient pressure, in the air lines to feed fuel at a desired pressure as it enters the float chamber 34. Assuming the vehicle to be on a comparatively steep upward incline, the tank 15' will be at a much lower level, relative to the carbureter, than would be the case were the car on a level stretch of road, and it would require a greater pressure in the gasoline tank to force fuel to the carbureter while on this incline than were the car on a level strip of road. And as the pressure of the fuel in the settling basin 32 decreases, the flexible diaphragm 42 will tend to straighten out, therefore, permitting the spring 48 to move the valve member 46 toward the port 47 in the valve casing 31, and finally closing the same, so that the full pressure on the pump 25 would be fed to the tank 15.'

However, if the tank is raised to a higher level, the pressure of the fuel in the settling chamber adjacent the carbureter, would tend to increase, thus expanding the diaphragm 42 to the position shown in dotted lines in Fig. 2, resulting in the lifting of the valve member 46 from its seat 47, and relieving the pressure of the air in the system by discharging a portion through this port, thus resulting in a decrease of the pressure of the fuel as it enters the carbureter to the

desired normal. This action of the valve mechanism will maintain a substantially constant pressure of the fuel as it enters the carbureter, regardless of the variation of the level of the fuel in tank.

It will, of course, be understood that by maintaining a substantially constant pressure of fuel as it enters the carbureter, it facilitates the maintenance of a proper level of the fuel in the float chamber of the carbureter, thus also facilitating the maintenance of a proper mixture of the gas produced by the carbureter. Of course, by altering the adjustment of the screw 50, the pressure in the air line may be changed, and thus vary the quality of the fuel mixture.

While we have described what we deem to be a preferred form of our invention, it will be obvious that various changes and modifications may be made, without departing from the spirit and scope thereof.

Having thus described our invention, what we claim and desire to secure by Letters Patent is:

1. In a liquid feeding system, the combination with a carbureter having a valve for regulating the supply of fuel thereto, and a fuel tank therefor, normally arranged at a level below said carbureter, of pressure means acting on said tank for feeding fuel from said tank to said carbureter comprising a regulating device adapted to be actuated by the pressure of the fuel adjacent said carbureter.

2. In a liquid feeding system, the combination with a carbureter having a valve for regulating the supply of fuel thereto, and a fuel tank therefor, normally arranged at a level below said carbureter, of pressure means for said tank, connections for feeding fuel from said tank to said carbureter, and a regulator arranged between said pressure means and said tank and adapted to be actuated by the pressure of the liquid in said connections at a point above said tank.

3. In a liquid feeding system, the combination with a carbureter having a valve for regulating the supply of fuel thereto, of a source of fuel supply therefor, comprising a pressure actuated regulator adapted to automatically provide a variable pressure at said supply source.

4. In a liquid feeding system, the combination with a carbureter, of means for feeding fuel thereto, comprising a source of supply normally arranged at a level below said carbureter, connections from said source to said carbureter, pressure means for feeding fuel from said source to said carbureter, and a regulator arranged between said pressure means and said source and adapted to be actuated by the pressure in said connections adjacent said carbureter.

5. In a liquid feeding system, the combination with a carbureter, comprising a float

chamber, a fuel tank normally arranged at a lower level than said carbureter, and pressure means for said tank, of a regulator arranged between said pressure means and said 5 tank and adapted to be actuated by the pressure of the fuel adjacent said float chamber.

6. In a liquid feeding system, the combination with a carbureter, of means for feeding fuel thereto, comprising a tank normally arranged at a level below said carbureter, pressure means for said tank, connections between said tank and said carbureter, comprising a settling chamber, and a regulator 10 between said pressure means and said tank, and adapted to be actuated by the pressure of the fuel in said settling chamber.

7. In a liquid feeding system, the combination with a carbureter, of means for feeding fuel thereto, comprising a tank normally arranged at a level lower than said carbureter, pressure means for said tank, connections therebetween, comprising a valve 20 device, connections between said tank and said carbureter, and means susceptible to 25

the pressure in said latter connections for actuating said valve device.

8. In a liquid feeding system, the combination with a carbureter, of means for feeding fuel thereto, comprising a tank normally arranged at a level below said carbureter, a pump for feeding pressure thereto, connections between said pump and said tank, comprising a valve device, connections between said tank and said carbureter, comprising a chamber, a diaphragm over said chamber, and means between said diaphragm and said valve device whereby the latter is adapted to be actuated by the pressure in said chamber. 30 35

9. The combination with a carbureter having a valve for regulating the supply of fuel thereto, of a connected source of fuel therefor, comprising a pressure regulator adapted to vary the quality of the fuel mixture by altering the pressure of the fuel. 40 45

In testimony whereof, we affix our signatures.

LYLE K. SNELL.
CHESTER F. JOHNSON.
